(57) **CLAIM**

We claim the ornamental design for a window chin rest for dogs, as shown and described.

DESCRIPTION

FIG. 1 is a perspective view of a window chin rest for dogs showing our new design;

FIG. 2 is a side view thereof;

FIG. 3 is a perspective view thereof showing the window chin rest for dogs installed over the window glass edge of an automobile window; and,

FIG. 4 is a perspective view thereof showing a dog hanging on the window chin rest for dogs.

The broken lines in the figures are included to show unclaimed subject matter or environment only, for illustrative purposes, and form no part of the claimed design.
